(57) **CLAIM**

I claim the ornamental design for the friction fit tool handle, as shown and described.

DESCRIPTION

FIG. 1 is a perspective view of a friction fit tool handle.

FIG. 2 is a top view of the friction fit tool handle.

FIG. 3 is a side view of the friction fit tool handle.

FIG. 4 is a perspective view of a top portion of the friction fit tool handle.

FIG. 5 is a top view of a top portion of the friction fit tool handle.

FIG. 6 is a side view of the top portion of the friction fit tool handle.

FIG. 7 is a perspective view of a bottom portion of the friction fit tool handle.

FIG. 8 is a top view of the bottom portion of the friction fit tool handle.

FIG. 9 is a side view of the bottom portion of the friction fit tool handle.

FIG. 10 is a rear view of the bottom portion of the friction fit tool handle.

FIG. 11 is a perspective view of the friction fit tool handle in partial assembly; and,

FIG. 12 is a perspective view of the friction fit tool handle in partial assembly.

The design is the external appearance of the friction fit tool handle as shown in the drawings. The broken lines are directed to portions of the friction fit tool handle that form no part of the claim.

1 Claim, 9 Drawing Sheets
